UNITED STATES PATENT OFFICE.

HENRY B. HAIGH, OF NEW YORK, N. Y.

DESIGN FOR A TOP LIFT FOR HEELS OF SHOES.

SPECIFICATION forming part of Design No. 32,598, dated April 24, 1900.

Application filed March 30, 1900. Serial No. 10,856. Term of patent 14 years.

To all whom it may concern:

Be it known that I, HENRY B. HAIGH, a citizen of the United States, residing in New York, (Brooklyn,) county of Kings, State of New York, have invented and produced a new and original Design for Top Lifts for Heels of Shoes, of which the following is a specification, reference being had to the accompanying drawings, forming part hereof.

Figure 1 is a perspective of a top lift, showing my new design. Fig. 2 is a cross-section of same.

As shown in the drawings, the leading or material feature of my design consists in the

top lift A, provided with a slot B, cut through 15 the top lift and extending in a semicircular or horseshoe shape. The slot is beveled, as shown at a in Fig. 2, from the outer surface of the top lift inward.

Having thus described my invention, what 20 I claim as new, and desire to secure by Letters Patent, is—

The design for a top lift for heels of shoes, as shown and described.

HENRY B. HAIGH.
